UNITED STATES PATENT OFFICE.

JOSEPH G. HUSS AND WILLIAM A. SMITH, OF MINNEAPOLIS, MINNESOTA.

SOIL-PIPE FITTING.

1,062,008.

Specification of Letters Patent. Patented May 20, 1913.

Application filed December 21, 1911. Serial No. 667,192.

To all whom it may concern:

Be it known that we, JOSEPH G. HUSS and WILLIAM A. SMITH, citizens of the United States, residing at Minneapolis, in the county of Hennepin and State of Minnesota, have invented certain new and useful Improvements in Soil-Pipe Fittings; and we do hereby declare the following to be a full, clear, and exact description of the invention, such as will enable others skilled in the art to which it appertains to make and use the same.

Our invention has for its object to provide an improved sanitary fitting especially adapted to be interposed in the main soil stack. This fitting is so arranged that the waste pipes discharging therein from lavatories, bath tubs, and the like, may be placed within the wall partition just back of the base board, instead of under the floor.

To the above ends, the invention consists of the novel devices and combinations of devices hereinafter described and defined in the claims.

25 The invention is illustrated in the accompanying drawings, wherein like characters indicate like parts throughout the several views.

Referring to the drawings:—Figure 1 is 30 a perspective view showing a portion of a bath room in which our invention is incorporated; Fig. 2 is a view partly in horizontal section and partly in plan showing the improved fitting on an enlarged scale; and Fig. 35 3 is a view partly in side elevation and partly in vertical section of the parts shown in Fig. 2.

For the purpose of showing the proper location of our invention, with respect to the 40 bath room furnishings, a portion of a bath room has been illustrated. The numerals 1 and 2 indicate, respectively, the floor and one of the wall partitions of the bath room. To the wall partition of the bathroom is 45 secured the customary base board 3. Within the bath room, is mounted the closet 4, lavatory 5, and bath tub 6, and which furnishings may be of any desired make or construction. Placed within the wall 2 is the 50 customary main soil stack 7. Interposed between certain sections of the main stack 7, and constituting a part thereof, is our improved fitting. In the drawings, this fitting is shown in the form of a cross, but may be 55 a T or any other desired form.

Referring in detail to the improved fitting,

the numeral 8 indicates a vertically extended body portion which forms a part of the stack 7. This body portion 8 is so arranged in the stack 7, that its upper end or hub portion extends slightly above the floor 1. Just below the floor 1, the body portion 8 is provided with an integrally formed, laterally extended, pipe extension 9 having a hub portion 10 adapted to receive the discharge end 60 of a waste pipe 11 from the closet 4. Integrally formed with the body portion 8, and on opposite sides thereof, is a pair of oppositely extended bends 12 terminating at their free or receiving ends in hubs 13. These 70 bends 12 extend at right angles to the pipe section 9 and their lower or discharge ends open into the body portion 8 at diametrically opposite points and in substantially the same horizontal plane with the discharge end of 75 the pipe extension 9. The bends 12 extend approximately vertically upward through the floor 1 and are then curved gradually away from the stack 7 until their hub ends 80 13 extend in a horizontal direction and rest upon the floor 1 between the walls of the partition 2, as best shown in Fig. 3. The hubs 13 of the bends 12 are adapted to receive the discharge ends of waste pipes 14. The waste pipes 14 are located between the 85 walls of the partition 2 and just back of the base board 3. Each bend 12 is provided, adjacent to its hub 13, with an integrally formed clean-out 15. These clean-outs 15 extend laterally and horizontally from the 90 bend 12 and are of such length as to project slightly through the base board 3, as best shown in Fig. 2. The outer ends of these clean-outs 15 are normally closed by means of nut caps 16 having screw threaded 95 engagement therewith. Each nut cap 16 is provided with an integrally formed annular flange 17 adapted to cover the opening of the base board 3 surrounding the clean-out 15. By reference to Fig. 2, it will be noted that 100 the clean-outs 15, on their vertical sides, are connected to the bends 12 by flat curves. This makes it comparatively easy to insert a wire into the clean-outs 15 and push the same through the bends 12, either toward the 105 stack 7, or into the waste pipe 14.

A vent pipe 18 connects the outer end of the right hand waste pipe 14 with the stack 7. The bath tub 6 is connected with the waste pipe 14, adjacent to the vent 18, by means of a suitable trap 19 located above the floor 1 and with its discharge end ex-

tending through the base board 3. The lavatory 5 is connected to a vertical extension 20 of the waste pipe 14 by means of a suitable trap 21, the discharge end of which extends 5 through the wall partition 2. To provide a suitable vent for the lavatory 5, the pipe section 20 is extended vertically upward at 22 and is connected at its upper end with the vent 18.

10 As is evident, by placing the waste pipe 14 within the wall partition 2, just back of the base board 3, the same may be easily cleaned at all times through the clean-out 15, or, if it is necessary to get at the pipe 15 itself in order to make repairs in case of a leak, the same may be reached by removing the base board 3.

At the present time, waste pipes, similar to 14 indicated in the drawings, are placed 20 under the floors. This necessitates the cutting of the joists which very materially weakens the building and, at the same time, there is more or less danger of the carpenters driving nails into the waste pipe at 25 the time the finished floor is being laid. It is also necessary to tear up the floor in case this pipe must be repaired; and it is also a very difficult matter to clean the same.

It may be here stated that it is impossible 30 to construct a fitting to take the place of the applicants' device, from fittings now found on the market, for the reason that they take up too much room in the limited space in which fittings of this character 35 must be placed.

What we claim is:

1. A fitting adapted to be interposed in a stack and having an integrally formed closet connection, and also having an integrally formed double bend tapping said stack at a point at least as far down as the discharge 55 end of said closet connection, and with its intermediate portion extending substantially parallel with said stack.

45 2. A fitting adapted to be interposed in a stack and having an integrally formed closet connection, and also having an integrally formed double bend tapping said stack at a

point at least as far down as the discharge end of said closet connection, and with its intermediate portion extending substantially parallel with said stack, and a normally closed clean-out on said bend.

3. A fitting adapted to be interposed in a stack and having an integrally formed closet connection, adapted to project below the floor, and also having an integrally formed double bend, adapted to project above the floor between the walls of a partition, said bend tapping said stack at a point at least as far down as the discharge end of said closet connection and with its intermediate portion extending substantially parallel with said stack.

4. A fitting adapted to be interposed in a stack and having an integrally formed closet connection, adapted to project below the floor, and also having an integrally formed double bend, adapted to project above the floor, between the walls of a partition, said bend tapping said stack at a point at least as far down as the discharge end of said closet connection, and with its intermediate portion extending substantially parallel with said stack, and a normally closed clean-out on said bend, adapted to project through the partition.

5. A fitting adapted to be interposed in a stack and having an integrally formed closet connection, adapted to project below the floor, and also having a pair of integrally formed diametrically opposite bends, adapted to project above the floor and between the walls of a partition, the discharge ends of said closet connection and said bends extending in substantially the same horizontal plane, and integrally formed normally closed clean-outs on said bends, adapted to project through the partition.

In testimony whereof we affix our signatures in presence of two witnesses.

JOSEPH G. HUSS.
WILLIAM A. SMITH.
